UNITED STATES PATENT OFFICE.

EDGAR D. HOSTLER, I. J. HAMIEL, AND CARL H. MATHER, OF TIPTON, IOWA,
ASSIGNORS OF ONE-HALF TO SAID HOSTLER, ONE-FOURTH TO SAID HAMIEL,
AND ONE-FOURTH TO SAID MATHER.

VULCANIZER.

1,379,447.

Specification of Letters Patent.

Patented May 24, 1921.

Application filed August 4, 1920. Serial No. 401,099.

To all whom it may concern:

Be it known that we, EDGAR D. HOSTLER, I. J. HAMIEL, and CARL H. MATHER, citizens of the United States, and residents of Tip-

5 ton, in the county of Cedar and State of Iowa, have invented a new and Improved Vulcanizer, of which the following is a full, clear, and exact description.

This invention relates to improvements in 10 vulcanizers, and more particularly to vulcanizers designed for connecting the ends of rubber tubes, such for example, as comprise the inner inflated tubes of wheel tires, an object of the invention being to provide a 15 vulcanizer which facilitates the vulcanizing operation either in the forming of a single or a double splice.

A further object is to provide a vulcanizer which is composed of sections readily inter- 20 changeable to give the desired shape and diameter in accordance with the size of the tube to be vulcanized.

A further object is to provide a vulcanizer which is relatively cheap to manufacture, 25 which can be conveniently used and attached to a table or support of any proper character and which is capable of a wide range of utility in the vulcanizing operation.

A further object is to improve upon the 30 construction disclosed in Patent Number 1338569, granted to E. D. Hostler April 27, 1920.

With these and other objects in view the invention consists in certain novel features 35 of construction, and combinations and arrangements of parts, as will be more fully hereinafter described and pointed out in the claims.

In the accompanying drawings—

40 Figure 1 is a view in side elevation of one section of our improved vulcanizer showing the tubes in section and in position for making a double splice.

Fig. 2 is a view in side elevation illustrating the complete vulcanizing apparatus 45 to form a double splice, showing the same secured to a heating table or other analogous support.

Fig. 3 is an enlarged top plan view of the 50 vulcanizer shown in Fig. 2.

Fig. 4 is a view of the vulcanizer shown in Fig. 3 provided with inserts to expand or increase the diameter of the vulcanizing surfaces.

Fig. 5 is a plan view illustrating a similar 55 type of vulcanizer shown in Fig. 3, but so constructed for attachment to the corner of a table.

Fig. 6 is a perspective view of one of the 60 inserts.

Figs. 7, 8, 9, 10, 11, 12, 13, 14 and 15 are views illustrating modifications.

Referring particularly to Figs. 1 to 6 inclusive, 1 and 2 represent two sections of one form of our improved vulcanizer. These 65 sections 1 and 2, when together, constitute in effect a tubular elbow forming two vulcanizing ends 3 and 4 at right angles to each other.

It will be noted particularly by reference 70 to Figs. 1 and 2, that the bore 5 of the elbow is of general elliptical shape, and this is due to the fact that the section 1 has a recess therein which is larger than the recess of the section 2, and it is to be understood that sections 1 and 2 will be provided with various sizes of such recesses so that when two of these sections are together, they will form a bore or tubular vulcanizing portions of any 75 desired shape and size in accordance with the 80 work to be done.

The sections 1 and 2 in their base portions 6 are made angularly, as shown at 7, to fit the end of a table 8 and this table 8 may have a steam or other heating chamber 9' 85 therein to heat the sections 1 and 2 to the necessary temperature for vulcanizing, and we may employ an ordinary clamp 10 to secure the sections to the table. Our invention is not, however, limited to the particular 90 manner of heating the sections as this may be accomplished in various ways.

In Fig. 4 we illustrate a means for expanding the vulcanizer to the desired diameter by placing metal inserts 11 between 95 the sections, one of these inserts being shown in perspective in Fig. 9, and it will be noted that the inserts have extended flanges 12 at their edges with rounded outer surfaces 13 to form a smooth surface for vul- 100 canizing.

In Fig. 5 we illustrate a vulcanizer with its base portion made with an angular recess 14 of such a shape as to fit the corner of the table 8 and provide a clamp 9 located at right angles to the sections. It will also be noted that we provide the sections 1 and 2 with relatively flat base flanges 15.

which facilitate the engagement of the clamp and also permits the clamp to hold the sections in proper formation for vulcanizing.

5 The vulcanizing operation carried out on this form of double splice is as follows: A rubber tube section 16 is projected through the bore 5 with its ends turned backwardly upon the outer faces of the tubular sections 10 3 and 4. The ends of the rubber tube A to be spliced are then positioned over and under the backwardly turned edges of the tube 16, said surfaces being cleaned with gasoline and surfaced with rubber cement, 15 or, in fact, treated by means of any desired process for carrying out the vulcanizing operation when the vulcanizing surfaces are heated, and as this invention is not limited to the particular process carried out, but 20 rather to the vulcanizing apparatus itself, we do not wish to be limited to the process employed.

In the modification illustrated in Figs. 7, 8, 9 and 10, we disclose a form of vulcanizer 25 which is designed for making a single splice. This vulcanizer also comprises two sections 17 and 18 having in their base portions recesses 19 having flattened lower surfaces to accommodate a clamp 20 to secure the 30 same to a heating table 21. These sections 17 and 18 are made with tubular portions 22, which, when together, form a continuous tube and the front of the sections are recessed, as shown at 23, to admit one end of 35 a tube 24 to be vulcanized. The end of this tube 24 is turned over against the outside of the tubular sections 22 and the other end of the tube 24 is located over and folded under the same and clamping strips or tape 40 25 are wound around the same and utilized in connection with ordinary vulcanizing cement to perfect the vulcanizing operation.

As shown in Fig. 10, the vulcanizer may be expended by the positioning of inserts 11 45 between the sections, the same as in the preferred form. This form of vulcanizer, shown in Figs. 7 to 10 inclusive, is made flat to rest directly upon a smooth topped table and be securely clamped thereon.

50 In the modification illustrated in Figs. 11 to 15 inclusive, the vulcanizer 26 is made integral with the heating table 27 and constitutes a single member having a slot 28 in one edge for the reception of an insert 29 55 corresponding to the inserts 11, and this insert is removed to allow the section tube to be conveniently removed from the vulcanizer after the vulcanizing operation is completed. In other respects, this vulcanizer corresponds in general shape and contour to the separable vulcanizer illustrated in Figs. 7 to 9 inclusive, with the exception that it constitutes a single part and is made integral with the table and is 60 65 not of two separable members as in Fig. 7.

With all forms of our improved vulcanizer, it will be noted that the vulcanizer itself is heated by means of a table or it may be heated from any other source and in several of the forms, the size or area of the vulcanizing surfaces and the diameter of the sections for accommodating the rubber tubes can be varied to suit conditions. This permits of a wide range of utility of the vulcanizer and permits the vulcanizer to be employed with an exterior vulcanizing surface or exterior vulcanizing surfaces which are readily accessible, which facilitate the junction of the tube sections, and which will permit the vulcanizing operation to be quickly, 70 75 80 efficiently and economically performed.

In vulcanizing the sections of the tube, we employ any desired method or material and do not limit ourselves to the particular method or process as my invention is intended to cover broadly the vulcanizer itself and any use to which this vulcanizer can be put.

In Fig. 14, we illustrate a modification in which a steam chamber 30 is formed as a 90 portion of the base of the vulcanizer itself.

Various other slight changes might be made in the general form and arrangement of parts described without departing from the invention, and hence we do not limit ourselves to the precise details set forth, but consider ourselves at liberty to make such changes and alterations as fairly fall within the spirit and scope of the appended claims.

We claim:

1. A vulcanizer, comprising a heating base, an upwardly projecting tubular portion on the base having an exterior vulcanizing surface, and said tubular portion having an entrance thereto for the accommodation 105 of a tube section to be vulcanized.

2. A vulcanizer adapted to be connected to a heater, said vulcanizer comprising two sections, said sections forming a tubular tube receiving portion having an exterior vulcanizing surface.

3. A vulcanizer adapted to be connected to a heater, said vulcanizer comprising two sections, said sections forming a tubular tube receiving portion having an exterior vulcanizing surface, and means for clamping said sections together.

4. A vulcanizer adapted to be connected to a heater, said vulcanizer comprising two sections, said sections forming a tubular tube receiving portion having an exterior vulcanizing surface, said sections of different cross-sectional area whereby the diameter of said vulcanizing portion is varied by the assemblage of sections.

5. A vulcanizer adapted to be connected to a heater, said vulcanizer comprising two sections, said sections forming a tubular tube receiving portion having an exterior vulcanizing surface, said sections having flattened 130

base portions adapted to receive a clamp to secure the same to a support.

6. A vulcanizer adapted to be connected to a heater, said vulcanizer comprising two sections, said sections forming a tubular tube receiving portion having an exterior vulcanizing surface, and removable inserts located between the sections and expanding the same.

10 7. A vulcanizer, comprising a pair of sections, said sections forming, when together, an elbow, and said elbow constituting at its

respective ends a pair of vulcanizing members having exterior vulcanizing surfaces.

8. A vulcanizer, comprising a pair of sections, each section having flat base portions and integral portions thereon forming, when together, a tubular vulcanizing portion, and means for permitting an expansion of said sections to vary the cross-sectional area of the vulcanizing portion.

EDGAR D. HOSTLER.

I. J. HAMIEL.
